CLAIM

The ornamental design for a dispenser for replacement cutter blades, as shown and described.

DESCRIPTION

FIG. 1 is a top view of a dispenser for replacement cutter blades showing our new design;

FIG. 2 is a bottom view thereof;

FIG. 3 is a right side view thereof;

FIG. 4 is a left side view thereof;

FIG. 5 is a front end view thereof;

FIG. 6 is a rear end view thereof;

FIG. 7 is a perspective view thereof with the blade holding mechanism extended; and,

FIG. 8 is a perspective view thereof with the blade holding mechanism retracted.

The undisclosed views of the blade holding mechanism of the dispenser for replacement cutter blades forms no part of the claimed design.
